(57) **CLAIM**

The ornamental design for a bottle holder, as shown and described.

DESCRIPTION

FIG. 1 is a left side perspective view of a bottle holder showing the new design;

FIG. 2 is a front view thereof;

FIG. 3 is a rear view thereof;

FIG. 4 is a right side view and a mirror image left side view thereof;

FIG. 5 is a top view thereof;

FIG. 6 is a bottom thereof; and,

FIG. 7 is another left side perspective view thereof.

The broken lines shown in FIG. 7 depict environmental subject matter and forms no part of the claimed design.

1 Claim, 7 Drawing Sheets---
